UNITED STATES PATENT OFFICE

159,007

SIGNAL LIGHT TELLTALE PANEL CABINET

James V. Schraig, Central Valley, N. Y.

Application November 10, 1949, Serial No. 5,980

Term of patent 7 years

(Cl. D26—5)

To all whom it may concern:

Be it known that I, James V. Schraig, a citizen of the United States, residing at Central Valley, in the county of Orange, in the State of New York, have invented a new, original, and ornamental Design for a Signal Light Telltale Panel Cabinet, of which the following is a specification, reference being had to the accompanying drawing, forming a part hereof.

Fig. 1 is a perspective view of a signal light telltale panel cabinet, showing my new design; Fig. 2 is a front elevational view; and Fig. 3 is a side elevational view.

I claim:

The ornamental design for a signal light telltale panel cabinet, as shown.

JAMES V. SCHraig.
